AUTOMATIC MECHANISM FOR OPERATING DRAWERS OF AUTOMATIC MUSICAL INSTRUMENTS

Filed Oct. 4, 1926

2 Sheets-Sheet 2

UNITED STATES PATENT OFFICE.

HUBERT J. LA JOIE, OF NEW YORK, N. Y., ASSIGNOR TO AUTO PNEUMATIC ACTION COMPANY, OF NEW YORK, N. Y., A CORPORATION OF NEW YORK.

AUTOMATIC MECHANISM FOR OPERATING DRAWERS OF AUTOMATIC MUSICAL INSTRUMENTS.

Application filed October 4, 1926. Serial No. 139,259.

It is customary in automatic musical instruments, particularly pneumatically operated grand player pianos, to arrange the music sheet manipulating mechanism in a drawer which can be moved in and out under the instrument case. This drawer is heavy and sometimes cramps so that the opening and closing thereof is difficult, particularly for a woman or child.

10 The object of the present invention is to provide an automatic mechanism under the control of the operator for opening or for closing or for both opening and closing the drawer. To do this, I secure a powerful 15 pneumatic such as a cylinder and piston on the bed of the musical instrument and connect the moving member thereof to the drawer. The operation of this pneumatic preferably is controlled by the setting of 20 the gearing which draws the music sheet forward or backward over the tracker-bar and this connection is preferably arranged so that the mechanism for operating the drawer will operate to open the drawer as 25 the re-rolling of the music sheet takes place.

The drawer operating mechanism is also arranged to close the drawer as the playing of the music sheet commences. This closing operation of the drawer operating mechanism is preferably controlled by a switch arranged in convenient position on the drawer so that the operator can start the music sheet in operation, adjust the tempo control, and then throw the drawer control switch so that the automatic mechanism which closes the drawer will work after the music sheet manipulating mechanism has been adjusted for the desired operation.

By these general combinations, the drawer 40 can be closed or opened or both opened and closed automatically, adding to the comfort of the operator.

The best form of apparatus for practicing the invention now known is shown in the 45 accompanying two sheets of drawings, referring to which

Fig. 1 is a general plan of the mechanism with my improvement applied thereto, the outline of the piano case being indicated in 50 dotted lines;

Fig. 2 is an enlarged plan view partly in diagram;

Fig. 3 is a detail of the re-play switch;

Fig. 3^a is a section through the movable part of said switch; and

Fig. 4 is a detail of the drawer control switch.

Referring to the drawings and in detail, D designates the drawer which has tracks running on rolls secured to the bottom of the piano case so that it can be moved in or out in the usual way.

The drawer D is kept from cramping as it is moved, by a shaft 10 journalled on the bottom of the piano case, which shaft has 65 bent ends 11-11 forming levers which are connected by links 110-110 to the drawer.

The drawer is provided with the usual middle compartment in which are arranged plungers or bearings for the music spool R, 70 the apertured tracker bar T and the take-up roll W. The apertures in the tracker bar are connected by tubes to the player action which may be secured to the bottom of the piano bed or which may be carried by the 75 drawer as is well understood.

The usual pneumatic motor M is arranged in the left hand compartment in the drawer. This motor drives a crank-shaft 12 having a sprocket gear 13, which by sprocket chain 80 14 drives a sprocket gear 15 secured on a driving shaft 16 slidably journalled in partitions in the drawer. This driving shaft 16 has a pinion 17 which can mesh with a gear 18 on the take-up roll W. A clutch 19 is 85 secured on said shaft 16 in position to engage or disengage with a sprocket gear 20 loosely journalled on the shaft 16. The gear 20 by a chain 21 drives a sprocket gear 22 secured on a shaft 23, which carries the right 90 hand bearing or spindle 24 for the music spool. The left end or usual spring-pressed spindle 25 for the music spool is arranged in line with spindle 24. Any ordinary music spool R can be snapped in between 95 and held in the bearings or spindles 24 and 25 in the usual way.

A pivoted lever 26 engages the clutch 19. This lever is connected by a rod 27 to the music sheet control button or knob 28. As 100 shown, the pinion 17 is in engagement with gear 18 and the music sheet S is being drawn forward over the tracker T for playing. If the music sheet control button 28 is moved to the left, the pinion 17 will be disengaged axially from gear 18 and the clutch 19 will 105

be engaged with the gear 20, whereby the music spool R will be rotated and the music sheet S will be drawn backward over the tracker bar T and rewound.

5 The rod 27 connects by a link 29 to a lever 30 pivoted to a shaft 31 journalled in the drawer partitions. This shaft carries a lever 32 at its rear end, which connects by a link 320 to a slidable rod 33.

10 A valve box V is secured to the rear of the drawer and carries a re-roll pneumatic P and a re-play pneumatic P'. A slidable rod 33 is loosely arranged in wings projecting from the pneumatics P and P' and is provided with adjustable collars 34—34 which said wings can engage.

15 A re-roll aperture 35 is arranged in the tracker T and is connected by tube 36 to the valve box V. Each music sheet is provided with a re-roll perforation 37. When the perforation 37 uncovers the aperture 35, the reroll pneumatic P is operated and the music sheet operating gearing is set so that the re-winding or re-rolling will take place.

20 25 The take-up roll W is provided with a groove w, in which is fitted a finger 38 secured on a small shaft 39, which shaft has a spring 40 normally moving the finger 38 into tight engagement with the take-up roll

30 35 W. A small lever or finger piece 41 is secured on the shaft 39 in position to engage a pivoted valve 42, which is pressed by a spring 43 into contact with a cut-off switch 44 which has a hole 45. The parts 41 to 45 are arranged in the drawer in the vicinity of the tracker in the usual way. This switch and the parts 41 to 45 are shown in diagram at the rear of the drawer to illustrate the operation.

40 45 50 A tube 46 extends from the hole 45 to a re-play switch RS. This replay switch is shown in detail in Figs. 3 and 3^a. When the re-play switch is in the position marked "off," the tube 46 connects by a tube 47 to the valve chest of a switch pneumatic SP secured to the rear of the drawer. The movable leaf of this switch pneumatic SP has an arm fitting on a rod 48 which has a collar 49. The rod 48 is connected to operate an electric switch ES, which controls the usual electric motor which drives the exhaust or suction pump. The rod 48 extends forward and has a button 480 on its end which forms a motor control which can be manipulated by the operator. If the replay switch RS is in position as previously described, when the music sheet S is rewound, the opening 45 is uncovered and the motor is stopped.

55 60 65 The re-play switch RS is also connected by a tube 50 to the valve box V. If the replay switch is set to "on" position when the aperture 45 is uncovered, the re-playing pneumatic P' will be operated and the switch pneumatic SP will not be operated. This

will start the playing operation over again whereby the piece of music represented by the particular music sheet in position will be re-played. This replaying will continue until the operator stops the mechanism.

70

The usual tempo control and motor governor are also arranged in the drawer as is well understood.

75 The parts previously described represent one well known form of mechanism of parts in a drawer of the character described. Any other known arrangement can be used as desired. The arrangements have been described in detail so that the cooperation of my improvements therewith can be understood.

80

With the usual arrangements it is necessary for the operator to pull out and push in the drawer.

85 The main object of the invention is to control the position of the drawer automatically so that it will be in its closed position when playing and so that it will automatically open when the playing is over.

90 To accomplish this purpose, the drawer is moved to open or closed position by a pneumatic which comprises a cylinder 51 secured to the piano case and having a piston 52 connected by an adjustable rod 53 to the drawer D. A pneumatic is preferably employed as the operating mechanism because it sometimes is desired to open the drawer while playing and this can be done against the pressure of the pneumatic. A valve box 54 is secured to the piano bed and the same is connected by a pipe 55 to the suction pump. A double valve 56 controlled by a diaphragm 57 is arranged in the valve box 54 and is connected by a tube 58 to the rear of the cylinder 51. Another double valve 59 operated by a diaphragm 60 is arranged in another compartment connected by a tube 61 to the front of the cylinder 51. A tube 62 extends from the space under the diaphragm 57 to a drawer control switch DC arranged in the drawer D. This drawer control switch DC connects by tube 63 to a hole 64 in a block 65 of a setting switch SS arranged in the drawer. This switch SS comprises a valve disc 66 pivoted on the block 65. The disc 66 has a notch 67 which opens and closes hole 64, a stop 68 being employed to limit the motion of the disc 66. A flexible tube 69 extends from the space under the diaphragm 60 to a hole 70 in the block 65, which is opened and closed by a hole 71 in the disc 66. The disc 66 is connected by a link 72 to a lever 73 on the shaft 31. The details of the drawer control switch DC are illustrated in Fig. 4.

115

120 125 The operation is substantially as follows:

Assuming the drawer to be in its outermost or front position, the operator places a music spool in position and connects the music sheet to the take-up roll. He then

130

throws the music sheet control button to the right and operates the motor control to start the suction pump in operation, so that the music sheet will be drawn forward over the tracker. If the drawer control switch DC is in "off" position, the tubes 62 and 63 are not in communication, and the drawer operating mechanism is out of operation as the music sheet is initially drawn forward over the tracker. This gives the operator the opportunity to set the tempo control. As soon as the parts are properly in operation, the operator throws the control switch DC to "on" position. This connects tube 15 62 and 63. Air is now admitted through openings 64, tube 63, tube 62 under diaphragm 57 which lifts the valve 56 to the position shown in Fig. 2. This connects the suction or tension of the pump X through 20 tube 58 with the rear of the cylinder 51. This will draw the piston 52 to the rear and will close the drawer. Air is admitted to the front of the piston 52 through pipe 61 so that this operation can take place. This 25 will close the drawer automatically without any effort on the part of the operator. The drawer control switch DC may be set in "on" position if desired before the apparatus is started in operation but it is usual to 30 start the music sheet properly in operation and set the tempo lever before operating the drawer control switch DC to close the drawer.

When the re-roll action starts as previously described, the setting switch SS is 35 shifted so that the hole 70 is uncovered and the hole 64 is covered. This permits air to pass through tube 69 under the diaphragm 60 which will operate the valve 59. This 40 will connect the suction pump with the front of the cylinder 51 through the tube 61, and the piston 52 will be drawn forward and the drawer opened as the valve 56 will move forward and connect the rear end of the cylinder to the atmosphere through tube 58. Thus as the re-rolling starts, the drawer will 45 be moved forward automatically to open position. If the re-play switch is off when the re-rolling is finished, the entire mechanism will stop operation and the drawer will 50 be left in its forward or open position. If the re-play switch is on when the re-rolling has been effected, the re-play pneumatic P' will be operated and the gearing will be 55 shifted so that the music sheet will be drawn forward again and as this operation takes place, the setting switch SS will be moved to the position shown in Fig. 2 and the valves 56 and 59 will be operated so that the 60 pneumatic 51 and 52 will pull the drawer into closed position. Thus the re-playing will take place with the drawer in closed position.

The entire drawer operating mechanism

can be kept in an inoperative position by 65 leaving the drawer control switch DC in "off" position. Thus the operator has the automatic operation of the drawer under his control.

This automatic operation of the drawer 70 forms a pleasing addition to the usual mechanism as it relieves the operator of the work and duty of moving the drawer in and out by hand. This is desirable because even with the present construction the drawer often 75 sticks and clamps and is difficult to move, particularly for a woman or a child.

The details and arrangements herein shown and described may be greatly varied 80 by a skilled mechanic without departing 85 from the scope of my invention as expressed in the claims.

Having thus fully described my invention, what I claim and desire to secure by 85 Letters Patent is:—

1. In an automatic musical instrument, the combination of a slideable drawer, music sheet manipulating mechanism carried by said drawer, and automatic mechanism mounted on said instrument and connected 90 to said drawer to open and close the same.

2. In a pneumatically operated musical instrument, the combination of a slideable drawer, music sheet manipulating mechanism carried thereby, and a pneumatic 95 mounted on said instrument and connected to said drawer to move the same.

3. In an automatic musical instrument, the combination of a slideable drawer carrying the music sheet manipulating gearing, 100 automatic mechanism for moving the drawer, and connections from the gearing for causing the mechanism to operate to open the drawer as the re-rolling of the music sheet takes place.

4. In a pneumatically operated musical instrument, the combination of a slideable drawer carrying the music sheet manipulating gearing, a pneumatic for moving the drawer, and a setting switch controlled by 110 said gearing for causing the said mechanism to operate to open the drawer as the re-rolling of the music sheet takes place.

5. In a pneumatically operated musical instrument, the combination of a slideable 115 drawer carrying the music sheet manipulating gearing, a pneumatic mechanism for moving the drawer, and a control switch on the drawer for controlling the operation of the pneumatic mechanism.

6. In a pneumatically operated musical instrument, the combination of a slideable drawer carrying the music sheet manipulating gearing, a pneumatic mechanism for moving the drawer, a setting switch controlled by the gearing for causing the pneumatic mechanism to open the drawer as the re-rolling of the music sheet takes place, and 125

a control switch on the drawer for throwing the pneumatic mechanism into operation to close the drawer.

7. In a pneumatically operated musical instrument, the combination of a slidable drawer carrying the music sheet manipulating gearing, a pneumatic mechanism for moving the drawer, and a setting switch controlled by the gearing for causing the pneumatic mechanism to operate to open the drawer as the re-rolling of the music sheet takes place, which setting switch also sets the parts so that the pneumatic mechanism will operate to move the drawer inwardly.
- 15 8. In a pneumatically operated musical instrument, the combination of a slidable drawer carrying the music sheet manipulating gearing, a pneumatic mechanism for moving the drawer, a setting switch controlled by the gearing for causing the pneu-

matic mechanism to operate to open the drawer as the re-rolling of the music sheet takes place, which setting switch also sets the parts so that the pneumatic mechanism will operate to move the drawer inwardly, 25 and a control switch on the drawer for holding the pneumatic mechanism out of operation until it is desired to close the drawer.

9. In an automatic musical instrument, the combination of a slidable drawer, music 30 sheet manipulating mechanism carried thereby, a pneumatic mounted on said instrument, a motor connected to said pneumatic, and connections between said pneumatic and said drawer whereby to permit movement of said 35 drawer by said pneumatic.

In testimony whereof I have hereunto affixed my signature.

HUBERT J. LA JOIE.
